2,508,940

TIMEPIECE REGULATOR

Oscar Edmond Dubois, Vevey, Switzerland

Application August 27, 1948, Serial No. 46,393
In Switzerland April 21, 1948

3 Claims. (Cl. 58—113)

1

The present invention relates to timepiece regulators and more particularly to a timepiece regulator comprising a balance spring guard pivoted upon the short shank of the regulator lever, laterally in relation to the curb pin, and so shaped as to be able to grip the hairspring against this pin by exerting upon it a pressure at least approximately at right angles to the hairspring at this point, an operating member for this guard consisting of a pseudo-regulator lever arranged on the upper face of the regulator, and by a locking and manipulating member for the regulator lever, this locking and manipulating member being concealed by the pseudo-regulator lever when the latter is in its hairspring gripping position, all in such a way that the hairspring, when once regulated, is nipped between the guard and the pin, so that no fresh regulation of the hairspring can be effected until after it has been released by displacing the pseudo-regulator lever to uncover the locking and manipulating member of the regulator lever.

One form of construction of the invention is illustrated by way of example in the accompanying drawings, in which:

Figure 1 is a plan view from above; and

Figure 2 is a view in side elevation.

In these drawings, 1 denotes the cock plank, carrying an end stone cap or index disc 2, on the serge of which is pivoted with lubricated friction a regulator lever 3, comprising an annular part 3a, a long shank 3b designed as an index member and terminating in a fork 3c, and a short shank 3d. The short shank 3d carries upon its under side a fixed pin 4 and a balance spring guard 5 pivoted upon a peg 6, arranged laterally in relation to the curb pin 4. The guard 5 is equipped with a nib or projection 5a, which is designed to force the hairspring 7 against the pin 4 by a movement at least approximately at right angles to the hairspring at this point, when the guard 5 is rocked by means of an operating lever 8, rigid with the peg 6, and forming a pseudo-regulator lever bearing upon the regulator lever 3. Between the limbs of the fork 3c of the regulator is pivoted, upon a pin 9, an eccentric 10, serving for the manipulating and locking of the regulator lever 3, and provided for the manipulation thereof with a diametral slot 11.

The pseudo-regulator lever 8 serving as an operating lever for the guard 5 has at its free end a circular portion 12, which, when the pseudo-regulator lever is so arranged that the guard 5 is in the position for locking the hairspring 7, completely covers the forked end 3c of the long

shank of the regulator lever 3 and the eccentric 10, the longitudinal axis of the pseudo-regulator lever 8 then coinciding with the longitudinal axis of the regulator lever 3. The pseudo-regulator lever is maintained in this position by a pin 13 engaging in a lateral notch 14 in the regulator lever long shank 3b.

This regulating mechanism has the advantage of not permitting readjustment of the hairspring 7 until after the guard 5 has been released by displacing the pseudo-regulator lever 8 to uncover the eccentric 10. When the adjustment has been effected the pseudo-regulator lever is returned to its place above the regulator lever, its pin 13 engaging in the slot 14, and the guard 5 again nipping the hairspring against the curb pin 4, by exerting upon it a pressure at right angles to the hairspring at this point.

What I claim is:

20. 1. A timepiece regulator comprising in combination a movable regulator lever having a long shank designed as an index and a short shank having a pair of members secured thereto for embracing the outer coil of a hairspring, said 25 pair of members comprising a stationary curb pin and a guard pivoted upon said short shank laterally in relation to said curb pin and so shaped as to be able to grip the hairspring against said curb pin by exerting upon it a pressure at least 30 approximately perpendicular on the hairspring at this point, an operating member for said pivoted guard consisting of a pseudo-regulator lever arranged on the upper face of said regulator lever, and locking and manipulating means for said 35 regulator lever concealed by said pseudo-regulator lever when the latter is in its hairspring gripping position, whereby no fresh regulation of the hairspring can be done until after said pseudo-regulator lever has been displaced to uncover said locking and manipulating member.

2. A timepiece regulator as claimed in claim 1, wherein said regulator lever is formed with a forked long shank and said manipulating and locking means is an eccentric arranged between 45 the limbs of said forked long shank and cooperating therewith.

3. A timepiece regulator as claimed in claim 1, wherein said long shank of the regulator lever is formed with a notch in which engages an abutment pin on said pseudo-regulator lever when the latter is in the hairspring gripping position.
